REVERSIBLE CIGAR BAND

Joseph Swarbrick, North Arlington, N. J.

Application December 29, 1949, Serial No. 6,908

Term of patent 3½ years

(CL. D85—9)

To all whom it may concern:

Be it known that I, Joseph Swarbrick, a citizen of the United States, residing in North Arlington, New Jersey, have invented a new, original, and ornamental Design for a Reversible Cigar Band, of which the following is a specification, reference being had to the accompanying drawing, forming a part hereof.

In the drawing:

Fig. 1 is a front elevational view of one side of a reversible cigar band showing my new design with the ends fragmented for convenience of illustration.

Fig. 2 is a front elevational view thereof taken from the rear of Fig. 1.

I claim:

The ornamental design for a reversible cigar band, as shown.

JOSEPH SWARBRICK.
